UNITED STATES PATENT OFFICE.

SAMUEL D. WHEELER, OF FOWLSTOWN, GEORGIA, ASSIGNOR OF ONE-HALF TO ISAAC B. GRIFFIN, OF FOWLSTOWN, GEORGIA.

HOISTING-SCAFFOLD.

SPECIFICATION forming part of Letters Patent No. 761,343, dated May 31, 1904.

Application filed December 9, 1903. Serial No. 184,463. (No model.)

To all whom it may concern:

Be it known that I, SAMUEL D. WHEELER, a citizen of the United States, residing at Fowlstown, in the county of Decatur and State 5 of Georgia, have invented a new and useful Hoisting-Scaffold, of which the following is a specification.

My invention relates to scaffolds such as are employed for raising workmen and their material to operate at an elevated position, and has for its objects to produce a comparatively simple inexpensive device of this character in which the raising and lowering operation may be readily performed by one occupying the 15 platform or scaffold proper.

With these and other objects in view the invention comprises the novel features of construction and combination of parts more fully hereinafter described.

20 In the accompanying drawings, Figure 1 is a side sectional elevation of a scaffold embodying my invention. Fig. 2 is an end elevation of the same.

Referring to the drawings, 1 designates a 25 supporting-base adapted to rest upon the ground and having a pair of spaced vertical standards 2 arising therefrom and connected at their upper ends by a cross-beam or other connecting-piece 3, said standards being 30 strengthened in their upright positions by diagonal bracing members or beams 4, extending between the same and the base 1, and are provided with longitudinal slots or ways 5.

6 designates the platform or scaffold proper, 35 composed of wood or other suitable material and having depending side walls 6^a secured to its longitudinal edges. Extending transversely between the walls 5 at the longitudinal center of the scaffold is a removable cylindrical rod or guide member 7, the ends of 40 which extend beyond the wall 6^a and travel in the slots or guideways 5 for guiding the scaffold in its upward and downward movements vertically of the standards 2. Depending 45 from the scaffold or platform are actuating and sustaining members 8, pivoted at their upper ends upon rods or pintles 9, extending between the side walls 6^a at points intermediate of the longitudinal center and opposite

ends of the scaffold, adjacent to which latter 50 theré also extend transversely between the side walls pivoting-rods 10, to which the members 8 may be shifted when found desirable, as hereinafter explained. These sustaining members, which consist, preferably, of metal 55 bars provided upon their outer edges with teeth or other engaging devices 11, are crossed one over the other to opposite sides of the longitudinal center of the scaffold and above a supporting member or rod 12, with which 60 the teeth 11 engage and which extends transversely between and is sustained by the standards 2 vertically beneath the guides 5. There are preferably four of the members 8, mounted in pairs upon the rods 9 and connected at 65 their lower ends by cross-pieces 13, to which are attached ropes or other flexible elements 14, extending upward through guide-openings 15 to the upper face of the platform 5.

Attached to the opposite ends of the platform 5 are ropes or other flexible elements 16, which are extended to and through a pulley 17, suspended from the cross-piece 3, said ropes being crossed to opposite sides of the pulley. There is also attached to and depending from the scaffold end operating-ropes 18, secured to the rods 10.

In practice when it is desired to raise the scaffold the operator pulls alternately upon the ropes 16, thus rocking the platform and 80 causing the members 8 to step upward tooth by tooth upon the support 12, or, in other words, first one pair of members 8, then the other, will move upward a distance of one tooth, it being understood, of course, that during said 85 movement the members swing by gravity into engagement with the support 12. When it becomes desirable to lower the scaffold, the operator grasps the ropes 16 and then pulls alternately upon the ropes 14, which action 90 swings first one pair and then the other of the members 8 out of engagement with the support 12, thus permitting them to move downward step by step or tooth by tooth until the scaffold has descended sufficiently. It will be understood, of course, that during both of these operations when one pair of members is out of 95 the other pair will be in engagement with

the bar 12 and that when the scaffold is at rest both pairs of the members engage the bar. The elevating operation may be performed from the ground by exerting traction upon 5 the ropes 18 to rock the platform. Also if it is desired to adjust the scaffold for a lower maximum height the members 8 are shifted to the pivots 10.

From the foregoing it is apparent that I 10 produce a simple and inexpensive device which will admirably perform its functions and one in which the raising and lowering of the scaffold may be performed by a person occupying the same. In attaining these ends I do not 15 limit myself to the precise details herein set forth, as minor changes may be made without departing from the spirit of the invention.

Having thus described my invention, what I claim is—

20 1. In a scaffold, the combination with a frame, of a support carried thereby, a platform sustained for vertical movement in the frame, crossed sustaining members connected with the platform and having teeth engaging 25 the support, said members being operable by the rocking of the platform for raising and lowering the latter, and means for rocking the platform.

2. In a scaffold, the combination with a 30 frame, of a support carried thereby, a platform sustained for vertical movement in the frame, crossed sustaining members pivotally connected with the platform and having teeth

engaging the support, said members being operable by the rocking of the platform for 35 raising and lowering the latter, a pulley sustained by the frame, and flexible elements extending through the pulley and connected with the platform for rocking the latter.

3. In a scaffold, the combination with a pair 40 of standards, of a transverse supporting-rod carried thereby, a platform having sliding connection with the standards, crossed sustaining members connected with the platform and having teeth engaging the rod, said members being operable by the rocking of the platform for raising and lowering the latter, and 45 means for rocking the platform.

4. In a scaffold, the combination with a 50 frame, of a horizontal supporting-rod carried thereby, a platform sustained for vertical movement in the frame, crossed sustaining members pivotally connected with the platform and having teeth for engaging the rod, said members being operable by the rocking 55 of the platform for raising and lowering of the latter, and operating-ropes for rocking the platform.

In testimony that I claim the foregoing as my own I have hereto affixed my signature in 60 the presence of two witnesses.

SAMUEL D. WHEELER.
